United States Patent Office.

HENRY STEPHENSON, WILLIAM THOMPSON, AND WILLIAM GREAVES BLAKE, OF SHEFFIELD, ENGLAND, ASSIGNEES TO FREDERIC W. GRIFFITH AND GEORGE P. BYRNE, OF NEW YORK CITY.

Letters Patent No. 101,535, dated April 5, 1870; antedated March 18, 1870.

IMPROVEMENT IN ORNAMENTAL-SCROLL TYPE.

The Schedule referred to in these Letters Patent and making part of the same

To all whom it may concern:

Be it known that we, HENRY STEPHENSON, WILLIAM THOMPSON, and WILLIAM GREAVES BLAKE, of Sheffield, in England, have invented a new and improved Type for Printing "Type-Ribbon;" and we do hereby declare that the following is a full, clear, and exact description thereof, which will enable others skilled in the art to make and use the same, reference being had to the accompanying drawings forming part of this specification.

This invention relates to a new and improved arrangement of type, whereby "type-ribbon," so called, may be printed in various forms by type set up in forms the same as printing-type.

The invention consists in a set of type of peculiar construction, which, when arranged together in a form, and with thick and thin brass or other metal rules, will represent the reverse of a design of "type"-ribbon, that is, a ribbon arranged in space and folded back and forth, so as to present two or more rows of plane surfaces, with intervals between, one above another, with diagonal parts between the rows, and terminating with waving ends, on which plane surfaces advertisements may be printed by ordinary printing-type set up in the forms with these improved type, all as hereinafter more fully specified.

Figure 1 is a view of a complete type-ribbon, printed on a card, and with an advertisement printed thereon;

Figure 2 is a face view of the type for printing the shading at the ends of the plane surfaces;

Figure 3 is a face view of the type for the ends of the ribbon;

Figure 4 is a face view of the type for long diagonals between the plane parts;

Figure 5 is a face view of type for short diagonals;

Figure 6 is a face view of type for intermediate diagonals; and

Figure 7 is an edge view of the rules for making the lines between the shading formed by the type, fig. 2, to indicate the plane surfaces.

Similar letters of reference indicate corresponding parts.

The face views of these type, as here represented, show the different forms required for producing, when

set up with lettered type, the print represented in fig. 1.

The type 1 1^a form the parts *a* representing the waving ends or terminals of the ribbon.

2 2^a form the shading at the turns *b* of these waving ends to the plane parts *C*, similar type being used at all the other turns *b*.

5 5^a represent the type for the long diagonals *d* between the lower and next row of plane surfaces.

3 3^a are the type for the short diagonals *e* between the middle and upper rows of plane surfaces; and

4 4^a represent medium diagonal type *f*, which may be substituted for either the long or short ones, or other intermediates, or longer or shorter diagonals may be used, as desired.

The straight lines *g*, fig. 7, represent the edges of the rules to be placed in the form to make the light line above and the heavy one below for the planes between the bends *b*.

As many duplicates of these type as may be required for the number of planes, folds, diagonals, and terminations, made in one print, may be used in one form.

Having thus described our invention,

We claim as new and desire to secure by Letters Patent—

The arrangement of the type 1 1^a to form the terminal *a*, 2 2^a to form the shadings *b*, 5 5^a to form long diagonals *d*, 3 3^a to form short diagonals *e*, and 4 4^a to form intermediate diagonals *f*, all located in a form, and combined with thick and thin metal rules *g* *g*, as and for the purpose specified.

The above specification of our invention signed by us this 22d day of December, 1869.

HENRY STEPHENSON.

WM. THOMPSON.

WILLIAM GREAVES BLAKE.

Witnesses for STEPHENSON and THOMPSON:

W. SMITH, Solr., Sheffield.

JOHN NIXON, clerk to Burberry & Smith, Sheffield.

Witnesses for BLAKE:

ALFRED PARKES, Notting Hill.

JAMES LEROY, London.
